MONORAIL TROLLEY

George C. Henderson, Detroit, Mich.

Application October 18, 1944, Serial No. 559,207

13 Claims. (Cl. 46—216)

1

This invention relates to monorail traction systems and particularly to trolleys for such systems.

An object of the invention is to provide a simplified yet highly efficient mechanism for driving a trolley-suspended carriage along a monorail.

Another object is to provide a drive mechanism for a trolley-suspended carriage that may be easily adapted to different suspended loads, to assure an adequate but not excessive tractive friction between a drive wheel and a monorail track.

Another object is to prevent in an improved manner side sway of a trolley in traveling a monorail.

Another object is to provide in an improved manner for securely holding a carriage suspending trolley engaged with its track, while affording it a ready removal from the track by means of a simple control.

Another object is to utilize monorail trolleys as coupling member for cars of a suspended train.

Another object is to suspend a car from an overhead track by trolleys riding the track and coupled to the end portions of the car.

Another object is to detachably couple the cars of a toy monorail train to the trolleys of the train, permitting different types of cars, such as passenger and freight to alternatively employ the same trolleys, thus reducing the cost of a train set including different types of cars.

These and various other objects are attained by the construction hereinafter described and illustrated in the accompanying drawings, wherein:

Fig. 1 is a view in side elevation of a train suspended on a monorail track by my improved trolleys.

Fig. 2 is a sectional view taken on the line 2—2 of Fig. 1, showing in end elevation the motor car of said train and its trolley.

Fig. 3 is a top plan view of the motor car trolley.

Fig. 4 is a vertical sectional view of the motor car trolley taken on the line 4—4 of Fig. 1.

Fig. 5 is a horizontal sectional view of said trolley taken on the line 5—5 of Fig. 1.

Fig. 6 is a vertical sectional view of the trailer trolley, taken on line 6—6 of Fig. 1.

In these views, the reference characters 1 and 2 designate upper and lower parallel rails spaced rigidly apart by insulating plates 3 to form a track for my improved trolley, such track being preferred at least for purposes of toy train sets. I have illustrated a train comprising a motor car 4 and passenger cars 5, all of toy design,

2

and have shown a drive-transmitting trolley associated with the motor car, and a mere suspension trolley associated with the passenger cars, said trolleys, however, having certain novel features in common.

Describing first the drive-transmitting trolley, a frame 6 which may advantageously be a sheet metal stamping rigidly surmounts the car 4 and projects upwardly therefrom, said frame having its lower end portion horizontally bent to form a base 1 bolted to the car as indicated at 8. It is preferred to extend said base forwardly and rearwardly beyond the car 4 and to perforate its ends for engagement by the downturned ends of coupling members 9 welded or otherwise permanently affixed to the cars 5. The upper end portion of the frame 6 is of reduced width and horizontally bent to form a lug 10 which journals the upper end of a shaft 11 adapted to be driven by an electric motor 12 rigidly installed within the car 4. The motor rigidly carries within said car an arched bracket 13 engaged by the bolts 8 and formed centrally with an upstanding bearing 14 journaling the motor shaft 14a and snugly engaging in an aperture of the base 1 to assure accurate alignment of the shafts 11 and 14a. A drive coupling between these shafts is established by forming one of them with a socket member 15 receiving the other, the latter transversely carrying a drive pin 16 engaging the socket member. Fixed on the shaft 11 just below the lug 10 is a small traction wheel 17 having its under face suitably beveled, as for example at a forty-five degree angle. Predetermined laterally spaced from the wheel 17 is a traction wheel 18 illustrated as cylindrical and mounted on a stub shaft 19 parallel to the shaft 11 and carried by the lug 10. As illustrated the free end portion of said lug is bent downwardly and then inwardly so as to support both ends of the stub shaft. The shafts 11 and 19 extend sufficiently above the lug 10 to carry a pair of intermeshed pinions 20 whereby the wheel 18 is driven reversely to the wheel 17. Spacing of the wheels 17 and 18 adapts them to seat on and straddle the track rail 1, said wheels and particularly the wheel 17 thus jointly transmitting the weight of the trolley, motor and motor car to said rail. Such weight induces a material pressure of such wheels upon the rail, particularly in view of the relative divergency of their rail-engaging faces.

A large rectangular aperture 21 in the upright portion of the frame 6 is productive of spaced parallel hanger arms and on each such arm is

mounted a sleeve comprising a plate 22 of fiber or other suitable insulation and a plate 23 of thin sheet metal, said plates being riveted together or otherwise permanently interconnected. The fiber plates of said sleeves face the track rail 2 and in each such plate is fixed a stub shaft 24 journaling a trolley wheel 25 grooved to straddle the rail 2. One of the described sleeves is fixed on its hanger arm by a rivet 26, the other being slidable up and down to permit disengagement of the corresponding trolley wheel from the track. A coiled spring 27 within the aperture 21 connects the slideable sleeve to the frame 6 and urges such sleeve upwardly with a force ordinarily assuring firm contact of the corresponding trolley wheel with the rail 2 under operating conditions. A strip of spring metal 28, welded to the sliding sleeve, projects freely above said sleeve and is terminally bent as indicated at 29 to overhang the frame and form a finger piece for use in manually flexing said strip clear of the frame. Thus said strip has the nature of a spring latch normally resisting any undue lowering of the sliding sleeve. A wire 30 soldered or otherwise electrically connected to the stub shaft of the spring-urged trolley wheel carries to one terminal of the motor current collected from the lower rail through said wheel, the other motor terminal deriving current through the frame 6 to which the rail 1 is grounded through the wheels 17 and 18.

The described arrangement assures against accidental escape of the motor car trolley from the track, while permitting an easy and expeditious removal or replacement when this is desired. Thus when the latch 28 is sprung clear of the upper edge of the frame, said latch serves as a handle for pushing down the sliding sleeve to allow disengagement of the corresponding trolley wheel from the track. The end of the trolley thus disengaged may then be tilted up at one side of the track so as to readily release the latter from the other end of the trolley. A reversal of these steps will obviously permit the trolley to operatively engage the track. It is necessary to provide the latch, additional to the spring 27, to safeguard the trolley, since the spring does not suffice under certain momentary conditions of operation. Thus when the trolley is traveling a curve of the track at considerable speed, the side thrust on the adjustable trolley wheel would overcome the spring in the absence of said latch, and also neglect to closely adjoin sections of the track might result in jolting said wheel clear of the track, if the latch were not provided. The spring is necessary additional to the latch, since the latter is not suited to maintain the firm contact essential to the current-collecting function of the adjustable trolley wheel.

Describing now the non-driving suspension trolley, a T-shaped frame 31 which may be a sheet metal stamping, has a pair of grooved wheels 32 journaled on the ends of its horizontal top portion to travel on the rail 1 and the upright stem of said frame mounts a third grooved wheel 33 to upwardly engage the rail 2. A sleeve 34 is slideable on said stem to carry the wheel 33 and a coiled spring 35 extending from such sleeve to the top portion of the frame urges the sleeve upwardly, normally assuring its proper electrical contact with the rail 2. Such contact is necessary in this type of trolley in case current is to be supplied to lights in the cars 5. A spring latch 36 which may duplicate the latch 28 already described resists any undue or accidental downward

sliding of the sleeve 34, and when released permits detachment of the trolley from the track. To support the cars 5 and couple them one to another, coupling members 37 attached to the ends of said cars have downturned ends engaging in apertures formed in the lower end of the frame 31 said end being horizontally bent. It is believed a unique feature of the described trolley system that the cars, other than the motor car, are each suspended between two trolleys and detachable from the latter. The resultant use of a trolley member as a means for coupling together two suspended cars is believed likewise novel.

It is a feature of the drive-transmitting trolley that same may be readily adapted to different suspended loads, as where toy trains are manufactured in various sizes, by substituting wheels 17 beveled more or less acutely than the illustrated wheel. The heavier the suspended load the less acute need be the included angle of bevel since the purpose of the bevel is to assure adequate driving friction in case the suspended load in itself fails to induce such friction.

It will be observed that the shaft 11 and that of the motor are slightly inclined to the vertical, the object of this inclination being to assure proper seating of the wheel 17 on the rail 1 without unduly reducing clearance of the shaft 11 from the track. In this connection it is to be noted that the wheel 17 is preferably very small so that the motor may have a maximum leverage in driving said wheel.

The simplicity and consequent low production cost of the described trolleys are highly desirable, contributing largely to the fact that monorail toy train sets as described may be produced at lesser cost than the more ordinary sets in which the track underlies the train.

A relatively thin fiber plate 24a is clamped between the plates 22 and 23 of each sleeve to prevent end contact of the stub shafts 24 with the arms mounting said sleeves.

What I claim is:

1. In a monorail trolley, a trolley wheel engageable with a rail, means resiliently holding said wheel normally engaged with said rail, and a spring latch element resisting escape of the wheel from the rail and manually flexible to afford such escape.
2. In a monorail trolley, a trolley frame, a trolley wheel engageable with a rail, and a latch element normally resiliently engaged with said frame to resist escape of the wheel from the rail, and manually releasable from such engagement.
3. In a monorail trolley, a trolley wheel operatively engageable with a rail, a trolley frame, a mounting for said wheel slideable on the frame transversely to the rail, means resiliently reacting between said frame and mounting to normally hold the wheel engaged with said rail, and a manually releasable spring latch means reacting between said mounting and frame to normally resist escape of the wheel from the rail.
4. A monorail trolley, comprising a trolley frame, a pair of spaced trolley wheels carried by the frame to engage a rail, means adapting one of said wheels for movement to and from the rail, means resiliently urging the wheel so adapted into engagement with the rail, and a manually releasable latch associated with said movable wheel and adapted to normally resist its movement from the rail.
5. In a monorail system, the combination with a track, and two carriages in train relation be-

neath the track, of a trolley arranged to travel on the track, and means for detachably coupling said carriages to and suspending them from said trolley, readily releasable from the trolley by lifting of the carriages.

6. In a monorail system, the combination with a track and two trolleys disposed to travel on the track, of an elongated carriage disposed beneath the track, and means for detachably coupling the end portions of the carriage to and suspending the carriage from said trolleys, said means being releasable from the trolleys by lifting of the carriage.

7. In a monorail trolley, a trolley frame, two wheels journaled in said frame and engageable with a monorail at opposite sides thereof, one of said wheels having a beveled face adapted to seat both downwardly and laterally against the rail and serving as a traction wheel, and means for driving said traction wheel to propel the trolley along the rail, the frame being apertured to accommodate said traction wheel.

8. In a monorail trolley, a trolley frame, two wheels journaled in said frame and engageable with a monorail at opposite sides thereof, one of said wheels having a beveled face adapted to seat both downwardly and laterally against the rail, and means for driving said wheels to propel the trolley along the rail.

9. A monorail trolley comprising a frame, a pair of wheels journaled upon said frame, spaced to straddle the top face of a track, drive means for at least one of said wheels to propel the trolley along the track, and a pair of grooved wheels journaled in said frame and oppositely spaced from the axial plane of the first mentioned pair of wheels and engageable with the track, beneath the latter, to resist lateral movement of the trolley relative to the track.

10. In a monorail trolley, a trolley frame, two ⁴⁰ wheels journaled in said frame and engageable

with a monorail at opposite sides thereof, one of said wheels having a beveled face adapted to seat both downwardly and laterally against the rail and serving as a traction wheel, said frame having a lateral extension above said wheels to dispose them in a straddling relation to the rail, and means for driving said traction wheel to propel the trolley along the rail, the frame being apertured to accommodate said traction wheel.

11. In a monorail trolley, a trolley frame having a lateral extension at its top, two wheels mounted in said frame beneath said extension and laterally spaced to engage a track in a straddling relation thereto, an approximately vertical shaft carrying and driving one of said wheels, and a pair of intermeshed gears above said extension transmitting a drive to the other wheel.

12. In a monorail trolley and track, the combination with a trolley frame disposed at one side of the track, of an approximately vertical shaft journaled in said frame, drive means for said shaft, a traction wheel fixed on the shaft and supported on the track at one side thereof, said frame having an extension above and across the track, and means carried by said extension engaging the track at the other side thereof to maintain operative engagement of said wheel with the track.

13. In a monorail system, the combination with a track and two carriages in train relation beneath the track, of a trolley arranged to travel along the track and comprising a frame, coupling elements mounted on the carriages and projecting above the trolley frame to suspend the carriages upon said frame, said elements having downturned ends and said frame being apertured to receive said ends, whereby the carriages are readily detachable from the trolley.

GEORGE C. HENDERSON.
